LIQUID FUEL BURNER

Rallston M. Sherman, Glastonbury, Conn., assignor to The Silent Glow Oil Burner Corporation, Hartford, Conn., a corporation of Connecticut

Application January 25, 1936, Serial No. 60,832

3 Claims. (Cl. 158—76)

This invention relates to apparatus for burning liquid fuel (herein referred to for descriptive purposes as oil), and deals more particularly with burners of the so-called gun type.

5 The invention has among other objects the conservation of heat imparted to the combustion chamber of such a burner, the providing of simple and effective means for adjusting the air supply to the burner, and means for effectively 10 directing the air from the air impeller to the burner.

These and other objects of the invention will be best understood from the following description when taken in connection with the accompanying 15 illustration of one specific embodiment thereof, while its scope will be more particularly pointed out in the appended claims.

In the drawings:

Fig. 1 is a plan view, partly in section, showing 20 the principal working parts of a burner embodying one form of the invention.

Fig. 2 is an elevation showing the air control device in closed position and looking from the front or nozzle end of the burner;

25 Fig. 3 is a central, vertical section of the rear part of the burner shown in Fig. 1 but on an enlarged scale; and

Fig. 4 is a section on the line 4—4 of Fig. 3 looking at the air control device from the impeller end of the burner.

Referring to the embodiment of the invention here submitted for illustrative purposes, the burner is equipped (Figs. 1 and 3) with a rotary air impeller 11 of the so-called Sirocco type having a 35 central air intake 13. The impeller is mounted on a driving shaft 15 and comprises a disc 17 and an opposed spaced annular plate 19 with interposed connecting multiple vanes or blades. On one side of the impeller and connected to the driving 40 shaft 15 is mounted an electric driving motor 21 (Fig. 1). On the opposite side the shaft may be connected to the usual oil pump (not herein shown).

The impeller is mounted in a housing 23, the 45 upper part of which is of generally cylindrical form, having its end wall facing the motor closed except for the opening through which the drive shaft extends, and the opposite side or end wall preferably with an air admission opening 25 50 aligned with the opening in the annular plate 19 of the impeller.

The impeller is mounted in eccentric relation to the peripheral walls of the housing and rotates in the direction of the arrow shown in Fig. 55 3, the air being drawn into the central air intake

and discharged forwardly through a prolonged straight tubular air conduit 27 into which the impeller housing merges.

Positioned axially within the conduit is the oil delivery pipe 29 terminating just short of the 5 conduit mouth in a nozzle 31, the pipe 29 having connection at its rear end to the oil supply pipe 33 entering the conduit laterally. Oil is supplied under pressure to the pipe 33 from the oil pump, the latter being fed from a main storage tank, 10 not shown. The pressure maintained and the form of nozzle provided are such as to cause the discharge of oil from the nozzle, without pre-mixture of air, in the form of a cone-shaped spray 15 of mechanically atomized oil.

To ignite the commingled oil and air the usual 20 sparking electrodes 35 are employed, positioned in advance of the nozzle and connected each to a conductor 37, the latter being mounted in rigid, non-conducting sleeves 39 of porcelain or other 25 like insulating material, the conductors entering the conduit through the bottom thereof, as indicated in Fig. 3.

On the installation of the burner, the forward 25 end of the conduit is entered into and sealed with in the wall 41 of the furnace (Fig. 1), the open mouth terminating preferably substantially flush with the inside of the wall of the combustion chamber and the combustion chamber being preferably sealed against any substantial admission of 30 air other than that entering through the conduit.

In the operation of a burner of this type, when the burner is stopped, as by the actuation of a room thermostat with the resultant stoppage of the motor 21 and impeller 11, oil delivery ceases 35 and the forced draft created by the impeller stops. But, unless preventative means are provided, the combustion chamber remains open to the continuous passage of a current of cold air through the air conduit which, on the stoppage of the 40 burner, is accelerated or intensified by the draft through the heated chimney. This tends quickly to chill the walls of the combustion chamber and the heat transfer walls of the furnace, depriving them of the heat previously imparted thereto and resulting in a large and unnecessary heat wastage. 45

For the effective conservation of such previously imparted heat and a more efficient operation of the fuel burning apparatus as a whole, there is herein provided means for substantially cutting off further delivery of air from the air conduit as soon as the burner ceases to function and the air impeller comes to rest, thereby protecting the 50 walls of the combustion chamber and the furnace 55

from the chilling effect of the otherwise cold entering air.

In the illustrated embodiment of the invention, such means is in the form of an automatically acting air valve or shutter device (indicated in Figs. 1 and 3 generally by the numeral 43) located in the air conduit itself and preferably closely adjacent the air receiving end thereof between the nozzle and the impeller, such device being adapted 10 to open automatically for the free passage of air when the impeller is operated but to close automatically when the impeller is stopped.

With such device means are also provided whereby the amount of air delivered by the air conduit when the burner is in operation may be predeterminately adjusted, the usual air valve or shutter at the air suction end of the impeller being unnecessary. Such device is also preferably so arranged as to beneficially control the path of the 20 air through the conduit.

This device (as best shown in Figs. 2, 3 and 4) comprises a series of metallic blades 45 (therein six in number) approximately flat, each blade being of generally triangular shape with an outer arc-shaped edge. Each blade at the inner and outer ends of one edge has a small corner flange 47 bent at right angles, by means of which flanges the blade is pivotally mounted on a pin or small rod 49 and on which it is held by the small disc-shaped cap piece 51 fixedly secured on the end of the pin. Each rod is fixedly secured to the sleeve 53, and projects radially therefrom, the pins being equally spaced around the periphery of the sleeve. The sleeve 53 is fixedly secured to the rear end of 35 the oil delivery pipe 29.

A torsion spring 55 encircles each pin, having one end fixed to the pin and the other extending over and lying against the face of the blade pivoted on such pin so that normally the blades are 40 urged by the light pressure of the spring in a direction causing them to assume a closed position, or that shown in Figs. 2 and 4 and in full lines in Fig. 3. They are held in this closed position by the small stop finger 57 (Fig. 2) projecting from the lower end of the free edge of the blade which encounters and is stopped by the pivoting pin 49 of the next adjacent blade.

The pivoted edge of each blade extends somewhat beyond the pivoting rod 49, and when the 50 blades are in closed position this extension is there overlapped by the free edge of the next adjoining blade. When in closed position the blades together provide a substantially disc-like closure, substantially fitting the inner cylindrical walls of 55 the air conduit, as shown in Fig. 4, with a minimum of clearance left sufficient only to allow the subsequent opening movement of the blades. In such closed position further passage of air through the conduit is substantially cut off.

60 When the impeller is started into operation, the blades under the pressure of the air delivered by the impeller automatically swing about their pivot points and open into some such position as is indicated by the dotted lines in Fig. 3, allowing 65 the free passage through the conduit of air delivered by the impeller. The amount of air so delivered, however, and the resulting capacity of the air control device are dependent upon the extent of the blade opening movement. This may be 70 predetermined and the air supply for the burner definitely fixed by the simple use of an adjustable blade stop. Herein this is provided by means of the collar 59 which is adjustably threaded on the outside of the sleeve 53 in front of the air control device and has its rear edge presented to the stop

finger 57 of each blade, as indicated by dotted lines in Fig. 3, which finger moves forwardly away from the pivot pin 49 when the blade undergoes its opening movement. The stop collar 59 may be adjusted to any desired position lengthwise of the 5 threaded portion of the sleeve 53 and there held fixed by a set screw or other means. This provides adjustable means whereby the opening of the blades resulting from its adjustment may be limited to any point between zero opening and 10 maximum, so that the air supply for the burner may be preadjusted by varying the extent of blade opening.

The adjustable blade stop may be made accessible for ready adjustment either by providing a removable section 61 for the top of the air conduit or by splitting the entire casing of the air impeller casing so that the upper part is removable, as described in my previously filed application, Serial No. 717,967, filed March 29, 1934.

The provision of the air adjustment device for predetermining the amount of air delivered to the burner, located in front of the air impeller, precludes the necessity of the use of a valve or shutter at the suction end of the impeller where such 25 throttling of the air tends both to reduce the efficiency of the air impeller and also to create irregularities in the density of the air at different points around the periphery of the air conduit.

It will be observed that when the air is being delivered by the impeller, the blades in opening assume a forwardly pitched relation which tends to convert the otherwise straight-way progressive movement of the air through the conduit into a movement characterized by rotation 35 as well as by progression, so that the rotative movement of the air thus produced becomes a true rotative movement of uniform characteristics throughout the conduit.

While I have herein shown and described for 40 the purposes of illustration one specific form of the invention, it is to be understood that extensive deviations may be made in the form, construction and relative arrangement of parts, all without departing from the spirit of the invention.

I claim:

1. A liquid fuel burning apparatus having a nozzle for the delivery of liquid fuel to a combustion chamber, an air delivery conduit surrounding said nozzle for delivering air to said combustion chamber to be commingled with said fuel, an air impeller for forcing air through said conduit, means between said impeller and the mouth of said conduit for automatically shutting off further substantial passage of air to the combustion chamber on the stoppage of the air impeller, the said means comprising a series of pivotally mounted blades and a plurality of axes extending outwardly from and arranged symmetrically about the axis of the conduit on which axes the blades are mounted, said blades normally forming a substantial closure for the conduit, and means for holding said blades closed but yieldable under the pressure of the air discharged by the impeller to permit them to swing to an open position to permit the passage of air through the conduit.

2. A liquid fuel burning apparatus having a nozzle for the delivery of liquid fuel to a combustion chamber, an air delivery conduit surrounding said nozzle for delivering air to said combustion chamber to be commingled with said fuel, an air impeller for forcing air through the conduit, means between said impeller and the

5 mouth of the conduit for imparting a rotative movement to the air passing through the conduit and for automatically shutting off further substantial passage of air to the combustion chamber on the stoppage of the air impeller, the said means comprising a series of pivotally mounted blades arranged around the axis of the conduit and overlapping to form normally a substantially disc-like closure for the latter, and
10 10 means normally moving said blades to a conduit closing position but yieldable when said blades receive the pressure of the air delivered by the impeller to permit said blades to swing to an open position in which they impart rotation to
15 air passing through the conduit.

3. A liquid fuel burning apparatus having a nozzle for the delivery of liquid fuel to a combustion chamber, a cylindrical air delivery conduit surrounding said nozzle for delivering air
20 to said combustion chamber to be commingled with said fuel, a rotary vaned air impeller for forcing air through said conduit, said impeller
having a central air intake, and means in said conduit near the air-receiving end thereof for automatically shutting off further substantial passage of air to the combustion chamber through said conduit on the stoppage of the air
5 impeller, the said means comprising a series of overlapping, segmental blades and a plurality of equally spaced, radial axes on which the blades are pivoted, said axes extending outwardly from the axis of the conduit, said blades forming a closure for the conduit when in overlapping position, means normally moving said blades to overlapping conduit-closing position but yieldable when said blades receive the pressure of the air delivered by the impeller to permit said blades
10 to swing to an open position to permit the passage of air through the conduit, and adjustable means for limiting the opening movement of the blades to predetermine the supply of air delivered by said air impeller through said conduit.

RALLSTON M. SHERMAN.
